UNITED STATES PATENT OFFICE.

GEORGE W. SMITH AND JOHN GARY, OF CONEMAUGH, PENNSYLVANIA.

FAN.

1,011,259.

Specification of Letters Patent. Patented Dec. 12, 1911.

Application filed June 15, 1910. Serial No. 567,073.

To all whom it may concern:

Be it known that we, GEORGE W. SMITH and JOHN GARY, citizens of the United States, residing at Conemaugh, in the county 5 of Cambria, State of Pennsylvania, have invented a new and useful Fan, of which the following is a specification.

The fan which is the subject of the present invention is designed more particularly 10 for use in saw mills for removing dust, shavings, etc.; and it is the object of the invention to provide a fan of this kind which will not clog or choke up, nor become unbalanced.

15 With this object in view, the invention consists in a novel construction and arrangement of blades to be hereinafter described and claimed, reference being had to the accompanying drawing forming a part of 20 this specification, in which drawing;

Figure 1 is a front elevation of the fan. Figs. 2 and 3 are sections on the lines 2—2 and 3—3, respectively, of Fig. 1.

In the drawing, 5 denotes a circular disk 25 suitably mounted on a shaft of the fan so as to rotate therewith, and serving as a support for the blades. The drawing omits the casing and shaft and shows the disk equipped with five blades, but their number 30 is immaterial, and may be varied at will to suit the size of the fan, or the particular conditions under which it is to be used.

Each blade of the fan is made from a segmental blank the straight edges 6 and 35 7 of which are arranged at right angles to each other. The edge portion 6 of each blank is secured to one face of the disk 5 by means of rivets 9 or the like, the blade being curved rearwardly and laterally away 40 from the edge 6 and thence forwardly in the direction of rotation of the disk and blades, thus giving a curved contour to the edge 7 and making the curved edge 8 of the blank the advancing edge of the bucket 45 formed by the curved blade. This curved advancing edge 8 of the blade is extended in advance of the edge 6 and said curved edge 8 gradually recedes rearwardly and inwardly from the outer portion of the

50 bucket and then forwardly, in the direction of rotation of the bucket, to the fixed straight edge 6. It will be noted that the blades are all spaced apart at their inner ends and, by curving the advancing edges 55 8 in the manner set forth, the spaces between the inner or feed ends of the blades are con-

siderably increased. It will be noted that the buckets are arranged radially upon the disks and are projected slightly beyond the periphery thereof although this last arrangement is not deemed necessary.

The fan is adapted to rotate within a suitable casing not shown, the direction of rotation being indicated by the arrow in Fig. 1. Sawdust or other material to be 65 acted on by the fan is sucked into the fan casing and into the space between the inner ends of the blades or buckets. The material is then thrown outwardly beyond the periphery of the disks by centrifugal force 70 and is discharged tangentially from the casing in which the fan is located. Should rags, ropes or the like be inadvertently fed to the fan, the advancing inner portions of the curved edges 8 will first engage them 75 and, by reason of the contour of these edges, they will ride over or along the said materials and gradually direct them into the feed ends of the buckets without danger of them becoming hung upon the blades because there are no angle portions presented 80 to the material and which are likely to be engaged thereby. As a result, clogging of the fan and its casing is prevented and any material fed into the casing and to the 85 space between the inner ends of the blades will be gathered up by the fan and ultimately discharged from the casing without injury either to the fan or to the casing. By arranging all of the blades or 90 buckets upon one side of the disk and by extending the shaft from the other side of the disk and not through the disk as ordinarily, a clear passage is provided between the disk and the inlet of the casing and 95 there is no shaft tending to obstruct the passage of material.

The blades may be reinforced along their edges 8 by strips 10 of any suitable material.

The inclosing casing of the fan has not been illustrated in the drawing as it forms no part of the present invention.

What is claimed is:

A fan including a disk, a shaft secured, 105 at one end, to the center of one side of the disk, and a series of buckets disposed radially upon the other side of the disk and spaced apart at their inner ends, each bucket being made up of a segmental blank 110 having straight edges disposed at right angles to each other, one straight edge por-

tion of each blank being secured to the disk, and each of the blanks being curved rearwardly from said secured straight edge portion and thence forwardly in the direction of rotation of the disk, the curved edge of the segmental blank constituting the curved advancing edge of the bucket and receding rearwardly from the outer toward the inner end of the bucket and thence 10 forwardly to the secured straight edge of the bucket, the other straight edge portion of the blank following the curvature of the bent blank, the inner portions of the curved

advancing edges of the buckets constituting means for deflecting materials toward the 15 center of the disk during the rotation of the disk and buckets.

In testimony that we claim the foregoing as our own, we have hereto affixed our signatures in the presence of two witnesses.

GEO. W. SMITH.
JOHN GARY.
